UNITED STATES PATENT OFFICE

2,363,758

WIRE STRIPPING TOOL

Ernest S. Thompson, Stockton, Calif.

Application August 11, 1943, Serial No. 498,201

2 Claims.

(Cl. 81—9.5)

This invention relates in general to an improved electrician's tool, and in particular the invention is directed to, and it is an object to provide, a manually actuated tool for cutting and stripping protective and insulative covers or sheaths from electric wire and cable; the tool being relatively light weight and small, and thus readily manipulated by one hand while the other hand supports the wire or object.

A further object of the present invention is to provide a stripping tool of the type described which is arranged to receive and support wires or cables of different diameters, and so that the tool is operative to ring cut or strip cut the cover of a cable or wire without any adjustment of the tool being necessary to the accomplishment of either operation. The tool, however, is provided with means for ready adjustment of the depth of cut of the cutting blade, if necessary.

A further object is to provide a tool which comprises a pair of intersecting, pivotally connecting handles having hand grips at one end, a cutting blade mounted on one handle at the other end and projecting toward the other handle, and a wire or cable receiving cradle mounted on said other handle adjacent and opening toward the blade; the cradle including a longitudinal and a transverse wire or cable receiving way whereby the blade can ring cut or strip cut, respectively.

An additional object of the invention is to provide a tool, as above, in which said cradle comprises four relatively short, rigid fingers fixed at their inner end on said other handle and extending therefrom generally and symmetrically toward said one handle but in divergent relation to each other, and 90° apart; the fingers being disposed at an angle of 45° relative to a line longitudinally of the tool so as to form, between adjacent ones of the fingers, longitudinal and transverse cable receiving ways.

It is also an object of this invention to provide a tool, as described, in which the handles include laterally projecting right angle extensions at their forward end to support said cutter blade and cradle, respectively, in laterally offset relation to the handles; the latter having loop-type hand grips which are canted laterally in the same direction as said blade and cradle are laterally offset.

A further object of the invention is to provide a simple and inexpensive device, and yet one which will be exceedingly effective for the purpose for which it is designed.

These objects I accomplish by means of such

structure and relative arrangement of parts as will fully appear by a perusal of the following specification and claims.

In the drawing similar characters of reference indicate corresponding parts in the several views:

Figure 1 is a side elevation of the tool showing, in dotted lines, a wire or cable engaged in the longitudinal way of the cradle.

Figure 2 is a cross section on line 2—2 of Fig. 1, and shows a wire or cable engaged in the transverse way of the cradle.

Figure 3 is a top view of the tool.

Referring now more particularly to the characters of reference on the drawing, my improved electrician's tool comprises a pair of intersecting handles 1 pivoted together intermediate their ends by a cross pin 2, as shown, or by a quick change step joint if it is desired that the tool accommodate work having a wide range of diameters. At their rear ends the handles 1 are formed with loop-type finger grips 3 canted laterally, as shown in Fig. 3.

At their forward ends the handles 1 are formed with generally parallel end portions 3 which include laterally projecting right angle extensions 5 and 6. The extensions 5 and 6 project laterally of the tool in the same direction that the loop-type finger grips 3 are canted.

Adjacent its outer end the lateral extension 5 is formed with a socket through which extends a blade shank 7 of a cutter blade 8; said socket being disposed so that said blade projects toward the lateral extension 6. The cutting or working edge 9 of the blade 8 faces longitudinally of the tool and rearwardly as shown. A set screw 10 is threaded into the end of the lateral extension 5 and engages the shank 7 of the cutter blade 8.

A wire or cable receiving cradle is mounted on the outer end of lateral extension 6 and opens toward the blade 8 in centered relation to the latter, said cradle comprising the following:

Four relatively short rigid fingers 11 are fixed at their inner end, as by welding, on the outer end portion of lateral extension 6, and project therefrom generally and symmetrically toward the lateral extension 5 but in divergent relation to each other, and 90° apart; said fingers being disposed at an angle of 45° relative to a line longitudinally of the tool so that the fingers 11 form a longitudinal wire or cable receiving way 12, and a transverse wire or cable receiving way 13.

In use of the tool, and to longitudinally strip a wire or cable, such wire or cable C is disposed in the longitudinal way 12 of the cradle,

and by squeezing the finger grips 3 the operator can effect and control the depth of penetration of the cutter blade 8 into the work. After such penetration of the blade, the tool is pulled lengthwise relative to the wire or cable C, resulting in a clean longitudinal cut. As the finger grips 3 are canted laterally, as described, the line of pull or force applied by the operator is substantially axially of the work.

To ring cut a wire or cable, the latter is disposed in the transverse way 13 of the cradle, as shown in Fig. 2, and the finger grips 3 squeezed together to penetrate the cutting blade 8. Thereafter, the tool and the work are relatively rotated through at least one full turn, resulting in the desired ring cut.

After the necessary ring and stripping cuts have been made in the sheath or cover of the wire or cable, the cut portion of said sheath or cover may be readily stripped off by hand.

By virtue of the particular construction of the cradle, the same is adapted to receive wires or cable of different diameters, without any adjustment of the tool being necessary. However, if the operator desires to limit or extend the depth of cut, this is readily accomplished by loosening the set screw 10 and resetting the shank 7 of cutter blade 8.

While the device is termed herein as a wire stripping tool, this term is intended to embrace a tool capable of both stripping and ringing cuts, as above described.

From the foregoing description it will be readily seen that I have produced such a device as substantially fulfills the objects of the invention as set forth herein.

5 While this specification sets forth in detail the present and preferred construction of the device, still in practice such deviations from such detail may be resorted to as do not form a departure from the spirit of the invention, as defined by the appended claims.

10 Having thus described my invention, what I claim as new and useful and desire to secure by Letters Patent is:

15 1. A wire stripping tool comprising a pair of supporting elements secured together for relative approaching and separating movement, a cutting blade mounted on one element and projecting toward the other element, and a wire receiving cradle mounted on the other element and opening toward said blade; said cradle being centered relative to the blade and comprising four rigid fingers fixed at their inner end on said other element and projecting in the direction of said one element in divergent relation to each other and approximately 90° apart.

20 2. A tool as in claim 1 in which said rigid fingers are disposed at an angle of approximately 45° relative to a line extending parallel to the blade.
